UNITED STATES PATENT OFFICE.

EDWARD HEYDE, OF EAST SAGINAW, MICHIGAN, ASSIGNOR TO THE WICKES BROTHERS, OF SAME PLACE.

SLIDE-VALVE.

SPECIFICATION forming part of Letters Patent No. 521,653, dated June 19, 1894.

Application filed December 23, 1893. Serial No. 494,567. (No model.)

To all whom it may concern:

Be it known that I, EDWARD HEYDE, of East Saginaw, Michigan, have invented certain new and useful Improvements in Slide-
5 Valves, of which the following is a specifica-
tion.

The object of my invention is to improve the construction of slide valves, and my improvements will be described in connection
10 with the accompanying drawings and par-
ticularly pointed out in the claims.

In the drawings, Figure 1 is a longitudinal sectional elevation through the valve with its casing and inlet. Fig. 2 is a transverse
15 central section. Fig. 3 is a longitudinal sectional elevation showing a modified construction; and Fig. 4 is a detail view of ring seg-
ments which I employ.

In the drawings, A represents the steam
20 chest having the eduction pipe B in one end thereof and a stuffing box C at the opposite end through which the valve rod D passes.

E represents the valve, which is shown in two forms in Figs. 1 and 3 respectively. The
25 middle portion of its body in both construc-
tions is turned off circumferentially to pro-
vide the steam outlet F and the valve is also
cored out or hollow so that the two ends of
the chest are in communication.

30 G, H represent ports which put the steam chest in communication with the cylinder below (not shown).

By reference to Fig. 2 of the drawings it will be seen that the ports G and H extend
35 through less than one-half of the circumfer-
ence of the valve; and in order that such ports may be controlled without undue friction or loss of steam, I employ a novel con-
struction as follows: The valve has its body
40 circumferentially grooved near its respective ends, the grooves being indicated at I, J, and in these grooves are secured the ring seg-
ments K, L, which are shown in elevation in Fig. 4 and in dotted lines in Fig. 2. The seg-
ment K, as will be seen, is longer than the
45 segment L so that the ends of the former extend below the longitudinal center of the valve chest. The lower segment L may be

fixedly secured by the pins k within its groove so that it will not drop out in passing
50 over the port. The upper segment K is mov-
ably mounted in the upper portion of the groove upon the springs M which are seated at their lower ends in the bosses O formed in
the perimeter of the valve and in apertures
55 transversely of the body thereof, which apertures open into the bottom of the groove. The springs are therefore free to exert a con-
stant outward pressure upon the movable ring segment, the result of which is to form
60 a suitable tight joint with the wall of the steam chest. By making said segment of a length greater than one-half of the circum-
ference of the valve it can be conveniently
mounted and at all times constantly forced
65 throughout its length outward against the
wall of the chest. It is also extended past
the ends of the ports in order to prevent any
leaking of steam at those points. Of course
the lower ring segment might be formed in-
70 tegrally with the valve, but I prefer to form
it separately as the construction is more eco-
nomical.

The operation of the valve need not be de-
scribed as it will be entirely familiar to those
75 acquainted with the use of slide valves.

By my construction I am enabled to secure a suitable steam tight joint by the employ-
ment of this movable packing ring and which
will be thrust out and maintained in constant
80 packing contact with the wall of the chest and self-compensating for wear upon its pe-
riphery.

Without limiting myself to precise details
of construction, I claim—

1. A slide valve construction, comprising
in combination, a steam chest having ports
through its bottom wall and terminating be-
low its longitudinal center, a valve having its
body circumferentially grooved toward its
90 ends, packing rings secured in the lower por-
tions of said grooves, and packing segments
mounted in the upper portions of said grooves
upon outwardly forcing springs, substantially
as described.

2. The combination with a valve chest hav-

ing ports extending through less than half of its circumference, a slide valve having its body circumferentially grooved toward its ends, packing rings of less length than the 5 ports secured in said grooves, packing segments movably supported in said grooves and having their ends above the ends of the ports

and outwardly forcing springs upon which the movable segments are mounted, substantially as described.

EDWARD HEYDE.
